Patented Sept. 30, 1919.

FIG. 1.

INVENTOR,
George A. Cole
BY
Wm. H. Cole, Jr.,
ATTORNEY

UNITED STATES PATENT OFFICE.

GEORGE A. COLE, OF NEW YORK, N. Y.

SIGNAL.

1,317,268.

Specification of Letters Patent. Patented Sept. 30, 1919.

Application filed August 16, 1917. Serial No. 186,443.

To all whom it may concern:

Be it known that I, GEORGE A. COLE, a citizen of the United States of America, residing at New York, N. Y., have invented a new and useful Signal; of which the following is a specification.

My invention relates to signals generally, the objects of the invention being to provide a simple and practical form of signal apparatus which may be used wherever a signal device of some sort is necessary or desirable.

My invention particularly has in view the provision of a signal suitable for railway crossings, draw bridges, railway trains and other vehicles.

Briefly considered, the invention comprises an oscillating member or hub, as I have termed it, carrying a resilient flexible stay supporting a signal head, together with a motor for positively oscillating the hub in opposite directions.

A special feature of the invention is the securing of the resilient flexible stay detachably in place so that it may be easily removed and be replaced by a new one when in need of repairs or the like.

Other features of the invention will appear as the specification proceeds. In the drawing accompanying the specification, I have illustrated my invention as embodied in a practical and preferred form, but I would have it understood that many changes and modifications may be made without departing from the true spirit and scope of the invention.

In said drawing:—

Figure 1 is a face view of the apparatus, with the protective housing or casing shown in section and showing further in diagrammatic form a suitable arrangement of circuit connections.

Fig. 2 is an enlarged longitudinal sectional view of the signal head and the oscillating hub which operates the same.

Fig. 3 is a broken perspective view of the oscillating hub member.

Fig. 4 is a detail view of the base member of the resilient signal arms.

In the construction illustrated, 10 designates the signal head, as I have termed it constructed to form a suitable signal. In the illustration, this head is of generally circular form and may be colored red or marked in any other distinguishing way. It is made hollow as indicated in the present case to contain a signal lamp 11.

The signal head is carried by a resilient flexible support which here is made up of two flexible stays 12 and 13, said stays being carried by an oscillating support or hub 14, as I have termed it, this hub being journaled at 15 in suitable supports 16.

The signal head is given a swinging or oscillating movement by means of a motor 17 connected with the oscillating hub by suitable gearing consisting in the illustration of a worm 18 on the shaft 19 of the motor, meshing with a worm gear 20 on the shaft 21, said shaft 21 carrying an eccentric 22 with which is engaged a rod 23 connected with the oscillating hub at 24.

The effect of the connections thus described is that when the motor is in operation, the oscillating hub is rapidly vibrated back and forth and this, through the resilient flexible stays imparts a swinging catapult movement to the signal head, causing said signal head to vibrate rapidly through a wide range of action.

By varying the speed of the motor or the ratio of gearing connections, it will be evident that the rate of vibration may be changed to produce different signal effects.

The motor or power device may be of any suitable construction and while I have shown an electric motor employed in the present instance, I would have it understood that any other type of motor may be employed. In any event, the motor is governed by a suitable controller, said controller consisting in the disclosure, of a circuit closer, made up of a bridging member 25, adapted to complete the circuit between two contacts 26, one of which is connected directly with the motor by wiring 27 and the other of which is connected with the motor by wiring 28, having a battery or other source of current 29 interposed therein.

The controller for the motor may be operated, according to the use to which the signal is put, as by the movement of a passing train, for a crossing signal, as by the movement of some part of the operating mechanism of a draw bridge, or by the application of brakes on the slowing down of a railway train or other vehicle.

The circuit for the signal device mounted in the signal head, in this case, the lamp 11, is provided in part, by the two resilient metal stays 12 and 13 which support the head, the current being led to the oscillating hub through flexible connections 30 and

31 which may be connected as indicated with the same source of current which supplies the motor.

As the more or less continuous flexing of 5 the resilient stays has a tendency to wear them out and as said stays sometimes break, due to over-tempering, flaws in the metal, etc., I have provided for the ready renewal of the entire signal carrying arm by securing 10 said arm to the oscillating hub in such a way that it may be readily attached to and detached therefrom.

In the illustration this is accomplished by securing the ends of the stays in a base piece 15 32 which is detachably secured to a corresponding base part 33 on the oscillating head as by means of securing screws 34. I have also provided for the completion of the electric circuit by the simple attachment 20 of one part to the other by providing on the base 32 circuit terminals 35, adapted to engage contact sockets 36 on the oscillating hub when the parts are brought together. This provides for an easy attachment of new 25 signal heads and without the necessity for independently manipulating any electrical connections. This feature of ready interchangeability is of considerable value in the case of railway, draw bridge, and the like 30 signals, which are more or less exposed to the weather, and enabling a quick repair by the substituting of new parts, and permitting of the old parts being taken away for purposes of repair at a more convenient time 35 and place.

Another feature of the structure illustrated is the provision of curved guides 37 at opposite sides of the flexible signal arms which form fulcrums over which the signal 40 arms may bend in the oscillation thereof, substantially as indicated in dotted lines in Fig. 1. This imparts a more gradual bend to the signal arm and thus to a certain extent frees the signal arm of strain and prevents breakage thereof.

It will be seen from the foregoing that the invention is adapted to a wide range of uses and it is capable of being easily installed wherever desired.

50 The signaling action may be controlled either manually or automatically—in this latter connection as by the opening of a draw bridge, approach of a train, the application of brakes, etc. Also the controller in 55 the case of railway trains may be arranged to be operated in conjunction with the throttle or controller of the train in such a way that when power is reduced or cut-off the signal will be thrown into operation.

60 The resilient signal carrying arms may be tapered in thickness or in width toward their free swinging ends so as to provide an extra degree of resiliency at the signal end of the arms. This strengthens and provides 65 a certain degree of reinforcement at the base

ends of the arms, where the arms are subjected to the greatest strain. In the illustration these arms are shown tapered in width and thickness but it will be understood that they may be tapered only in one 70 direction.

The signal swinging downward as it does, has a pendulum action and the parts are preferably so proportioned as to the weight of the signal head, the resiliency of the 75 spring arms, the speed of the motor and the gearing connections between the motor and the oscillating hub that the signal head will vibrate substantially at the true rate of vibration of a pendulum of that particular 80 length. This provides for a uniform movement of the swinging signal head and avoids the erratic action which would occur if the motor and swinging arm were not properly timed with respect to each other. Also with 85 this construction, where the swinging signal arm has a resilient catapult action it is only necessary for the motor to impart a relatively slight oscillating movement to the oscillating hub, the full swing of the signal 90 head being provided by the flexure of the signal arm at the end of the stroke in each direction. This swinging catapult movement also is assisted by thus swinging the signal arm as a pendulum. Another advantage 95 of this inverted construction is that the parts can be practically completely housed at all times.

I claim—

1. Signal apparatus comprising; a movable support, a signal head, a resilient flexible connection between the signal head and support, and a power device for imparting positive movement to said support in opposite directions whereby an amplified swinging movement will be imparted to the signal head in both directions. 100

40 2. Signal apparatus comprising, an oscillating support, a signal head, a resilient flexible connection between the signal head and support, and a power device for imparting positive oscillating movement to said support in opposite directions whereby an amplified swinging movement will be imparted to the signal head in both directions. 105

50 3. Signal apparatus comprising, an oscillating support, a signal head including an electric light, a resilient connection between said support and head, a power device including an electric motor for imparting a positive movement to said support in both directions to in turn impart an amplified swinging movement to the signal head in both directions, and electrical connections to close a circuit through the electric light and said motor for simultaneous operation of said light and motor. 120

60 4. Signal apparatus comprising a hub journaled for oscillatory movement, said hub having a plurality of insulated portions, a 125

65 130

resilient flexible stay carried by one of said hub portions, a signal head carried by said stay, a motor, gearing from said motor for oscillating the hub and a controller for the 5 motor, an electric lamp carried by the signal head and a controlling circuit for said lamp, said stay and insulated hub portions forming part of said circuit.

5. Signal apparatus comprising an oscillating hub, a resilient flexible support carried by said hub, a signal head carried by said resilient flexible support and curved guides on the oscillating hub at opposite sides of the resilient support and adapted 10 to form bearings over which said resilient support may bend in the oscillation of the signal head.

6. Signal apparatus comprising an oscil-

lating hub, a resilient flexible support carried by said hub, a signal head carried by 20 the resilient flexible support, a motor for positively oscillating the hub in opposite directions and curved guides on the oscillating hub at opposite sides of the resilient flexible support forming bearings over which said 25 resilient flexible support may bend in the oscillation thereof.

7. In a signal apparatus, a swinging pendulum comprising a pivoted support, a resilient flexible stay carried thereby and a 30 signal head carried by the lower end of said stay, a power device and operating connections from said power device for positively swinging said pendulum in opposite direction with a double catapult movement.

GEORGE A. COLE.
